UNITED STATES PATENT OFFICE.

JOHN G. BOUSLOG, OF ANAHEIM, CALIFORNIA.

ROD RACK.

Application filed November 1, 1924. Serial No. 747,260.

This invention relates to means for suspending lengths of sucker rod such as are used in oil wells and the like, the suspension means being mounted in the upper part 5 of the well derrick and engaging the lengths of sucker rod so as to suspend the latter therefrom in the derrick; and it is the object of the invention to provide safety means for engaging the suspended sucker rods so as to 10 positively prevent displacement thereof from their support.

The safety mechanism is particularly adapted for use in connection with suspension means comprising a rack having a 15 plurality of slots in its edge, so that one or more lengths of sucker rod may be received in each slot with the enlargements at the ends of the sucker rods resting upon the walls of the slots for supporting the rods; 20 it being understood however that the safety device is also adapted for general use in connection with any type of suspension means for sucker rods or the like.

The invention will be readily understood 25 from the following description of the accompanying drawings, in which:

Fig. 1 is a vertical section through a well derrick showing the improved rod rack mounted therein.

Fig. 2 is a front elevation of the rod rack partly in vertical section.

Fig. 3 is a transverse section on the line 3—3 of Fig. 2.

Fig. 4 is a fragmentary front elevation of 35 a rod rack, partly in vertical section and showing a modified form of the invention.

In the drawings I have shown a well derrick at 1, the particular construction of 40 said derrick forming no part of this invention. The rack for supporting lengths of sucker rod 2 is suspended in said derrick by a cable 3 which may be suitably connected to the crown block 4.

In the embodiment of the invention illustrated, the rod rack comprises a disc 5 having radial slots 6 extending inwardly from its outer edge, and provided with upturned peripheral lips 7 between the slots.

A suitable supporting connection is provided between disc 5 and the cable 3, which in the present instance is shown as comprising a tripod 8 extending upwardly from the disc, and a hook 9 supported by said tripod and adapted to be engaged by the cable. 55 The sucker rods 2 which are to be suspended from the rack are elevated in usual

manner until the coupling enlargements 10 at their upper ends are above disc 5, and the rack having been turned to position any desired slot 6 opposite the sucker rods, the latter are pulled over into the slot and are then lowered until their coupling enlargements rest upon disc 5, thereby maintaining the sucker rods suspended in the derrick after the elevator has been disengaged 65 therefrom.

When the sucker rods are thus suspended from the rack, the lips 7 at the periphery of disc 5 will engage the coupling enlargement 10 of the outer rod in each slot, in 70 order to prevent accidental displacement of the rods from the slots; but since these lips do not provide a positive lock for retaining the rods in the slots, there is always the possibility of accidental displacement, resulting in the dropping of a length of 75 sucker rod and the probability of serious injury.

The present invention provides positive means for locking the sucker rods relative 80 to their supporting rack. As an instance of this arrangement engaging means in alignment with the respective slots of the rack, are mounted on said rack and are adapted to be received around the sucker 85 rods in the respective slots, so as to prevent outward movement of the rods in the slots and thus maintain a positive suspension for said rods.

The engaging means illustrated in Figs. 90 2 and 3, comprise elongated closed loops 11, of a size to be received over the ends of all the sucker rods in any one slot of the rack, said loops being preferably suspended by short chains 12 from an annulus 13 which 95 is mounted on the rod rack above disc 5. When a sucker rod held in its slot by a loop 11, is to be withdrawn, the loop is first removed from the rod and positioned over the ends of the remaining rods in the slot, and a usual elevator is then connected to the released rod for lifting it from its slot and lowering it into the bore of the well.

A modified form of engaging means as 100 illustrated in Fig. 4, comprises hooks 11^a 105 connected to annulus 13 by the chains 12, the shanks of said hooks being of length to permit them being hooked around the outer sucker rods in the respective slots of the rack, in order to lock all of said sucker rods 110 in the slots as previously described. The hooks are preferably held against lateral

displacement and consequent disengagement from the sucker rods, by lugs 14 depending from the outer ends of the hooks and adapted to be received in slots 6 when the hooks 5 are in operative position. By the hook arrangements as thus described, when a sucker rod is to be withdrawn from the rack the usual elevator is first connected to the sucker rod, and the hook is then disengaged from 10 the sucker rod held by the elevator and hooked around the remaining rods in the slot. It will thus be seen that the rod which is being withdrawn is never free for accidental dropping; and the remaining rods in 15 a slot, even if they catch upon the rod which is being withdrawn, are positively held against displacement from their slot.

The annulus 13 supporting the engaging means as thus described, is preferably 20 mounted on a spider 15 having a bolt 16 depending from its center through an aperture in disc 5, the spider being held in place by nuts threaded onto the bolt in usual manner. A further support for annulus 13 is 25 preferably provided by projecting the legs of tripod 8 through suitable bores 17 formed on said annulus, the legs of the tripod being detachably connected to disc 5 by nuts threaded onto the ends of the legs, in order 30 that the parts may be thus assembled. The supporting annulus is thus positively fixed relative to the rod rack, so as to aline engaging means 11 or 11^a with the respective slots 6, and permit said engaging means to 35 be readily received around the sucker rods in the respective slots.

It will thus be seen that I have provided 40 extremely simple but positive means for holding sucker rods or the like against displacement from a support for the same, said engaging means being applicable to either a slotted rack as described, or any other type 45 of suspension means; and that said engaging means may be readily mounted upon and secured to the supporting device, in position for conveniently engaging or disengaging the sucker rods carried thereby.

I claim:

1. Suspension means for sucker rods having coupling collars comprising a support 50 having a recess, a retaining member, and a flexible connection between the support and retaining member, the recess of the support being adapted for lateral reception of a sucker rod with the walls of the recess engaged by the coupling collar of the sucker rod so as to support the rod against longitudinal displacement independently of the retaining member, and the retaining member 55 being adapted to be removably received around a sucker rod supported in the recess so as to prevent transverse displacement of the rod.

2. Suspension means for sucker rods comprising a member having a recess adapted

to receive a sucker rod so as to hold the same against longitudinal displacement, retaining means adapted to extend across the recess in front of a sucker rod therein so as to prevent transverse displacement of the 70 rod, and means on said retaining means adapted to be received in said recess for releasably holding the retaining means against movement laterally of the recess.

3. Suspension means for sucker rods comprising a member having a recess adapted to receive a sucker rod so as to hold the same against longitudinal displacement, a hook connected to said member and adapted to be received around said sucker rod so as to prevent transverse displacement thereof, and means on said hook adapted to be received in said recess for releasably holding said hook against movement laterally of said recess.

4. Suspension means for sucker rods comprising a member having a recess adapted to receive a sucker rod so as to hold the same against longitudinal displacement, suspension means for said member, and retaining means adapted to extend across the recess in front of a sucker rod therein so as to prevent transverse displacement of the rod, said retaining means being independent of the recessed member and connected to the 95 suspension means.

5. Suspension means for sucker rods comprising a disc having radial slots opening from the periphery thereof, said slots being adapted to receive and support sucker rods against longitudinal displacement, a suspension rod for said disc, retaining means independent of the slotted disc adapted to extend across the respective slots in front of the sucker rods therein so as to prevent transverse displacement of the rods, and connections between said retaining means and said suspension rod.

6. Suspension means for sucker rods comprising a member having a recess adapted to receive a sucker rod so as to hold the same against longitudinal displacement, a suspension rod for said member, engaging means adapted to be received around said sucker rod so as to prevent transverse displacement thereof, a member detachably mounted on said suspension rod, and a flexible connection between said detachable member and said engaging means.

7. Suspension means for sucker rods comprising a disc having radial slots extending inwardly from the periphery thereof, said slots being adapted to receive sucker rods with the shoulders of the latter resting upon the side walls of said slots, a suspension rod detachably connected to said disc and arranged for turning of said disc, an annulus on said rod supported by said disc in spaced relation above the same, flexible connections on said annulus in alinement with 130

the respective slots, and engaging means fixed at their inner ends to the respective flexible connections and adapted to be received around the sucker rods in the respective 5 slots so as to prevent transverse displacement thereof.

8. Suspension means for sucker rods comprising a support having a recess, and a retaining member, said recess opening into the 10 support and adapted for lateral reception of a sucker rod with the walls of the recess engaging the rod independently of the retaining member so as to hold the rod against longitudinal displacement, and the retaining 15 member being adapted for movement transversely of the recess and for limited shifting along the recess toward its open end so as to be received around a sucker rod supported in the recess and thereby prevent lateral displacement of the rod.

9. Suspension means for sucker rods having coupling collars comprising a support and displaceable retaining means cooperating therewith, the support having a recess 25 opening into the same and adapted for lateral reception of a sucker rod with the walls of the recess engaged by the coupling collar of the rod when the retaining means is displaced so as to hold the rod against longitudinal displacement independently of the 30 retaining means, and the displaceable re-

taining means being adapted for movement to operative position after the sucker rod is engaged by the walls of the recess, said retaining means when in operative position 35 completely bridging the recess between its open end and a sucker rod supported therein so as to prevent lateral displacement of the rod.

10. Suspension means for sucker rods having coupling collars, comprising a support and displaceable retaining means cooperating therewith, the support having a recess adapted for lateral reception of a sucker rod with the walls of the recess engaged 45 by the coupling collar of the sucker rod when the retaining means is displaced, the walls of the recess thereby holding the sucker rod against longitudinal displacement independently of the retaining means, and the displaceable retaining means being adapted for movement to operative position after the walls of the recess engage the coupling collar of the sucker rod, said retaining means when in operative position extending across the 50 recess between its open end and the supported sucker rod so as to prevent lateral displacement of the rod.

In testimony whereof I have affixed my signature to this specification.

JOHN G. BOUSLOG.
